UNITED STATES PATENT OFFICE.

SAMUEL R. PARKER AND PAUL P. DEVENY, OF PLYMOUTH, OHIO.

SHIFTING-RAIL FOR BUGGY-SEATS.

SPECIFICATION forming part of Letters Patent No. 280,660, dated July 3, 1883.

Application filed May 5, 1883. (No model.)

To all whom it may concern:

Be it known that we, SAMUEL R. PARKER and PAUL P. DEVENY, citizens of the United States, and residents of Plymouth, in the county of Richland and State of Ohio, have invented certain new and useful Improvements in Shifting-Rails for Buggy-Seats; and we do hereby declare that the following is a full, clear, and exact description of the invention, which will enable others skilled in the art to which it appertains to make and use the same, reference being had to the accompanying drawings, which form a part of this specification, in which—

15 Figure 1 is a perspective view of a buggy-seat provided with our improvement. Fig. 2 is a similar view, showing the top rail removed, but leaving the lazy-back in position on the seat. Fig. 3 is a perspective view of the 20 seat with both the lazy-back and top rail removed; and Fig. 4 is a sectional view, on an enlarged scale, through one of the seat-irons, showing the manner of attaching the top rail and lazy-back.

25 Similar letters of reference indicate corresponding parts in all the figures.

Our invention relates to the seats of buggies and other vehicles; and it consists in the combination, with the seat, of a removable top rail 30 for the attachment of a vehicle-top, and, also, of a removable lazy-back, which may be used either in conjunction with or without the top rail, as and for the purpose hereinafter more fully set forth.

35 In the accompanying drawings, A denotes the seat, and B the fixed sides and back of the same.

C are the seat-irons, which have extensions C', provided with holes c, as shown more clearly 40 in the detailed view, Fig. 4, of the drawings. The seat-sides are also provided with bracket-irons D, which have similar holes or apertures, d.

L is the lazy-back, and F the rail for the 45 same, which is provided with screw-threaded lugs f, adapted to be inserted through the apertures c of the seat-irons, to which they are nutted by the thumb-nuts G.

E is the top rail, which is provided with lat-

eral arms I, to which the buggy-top is attached 50 in the usual manner. The top rail, E, is provided with laterally-projecting lugs h, which are screw-threaded and inserted through the free ends of the rail F of the lazy-back, to which they are fastened by means of removable nuts 55 H, of any desired construction.

From the foregoing description, taken in connection with the drawings, the operation and advantages of our improvement will readily be understood without requiring lengthy explanation. It will be seen that by simply unscrewing the nuts G, the lazy-back, as well as the top rail, and the top attached thereto, may be removed from the seat in a moment of time and with very little trouble; while, by unscrewing the nuts H, the lazy-back may be detached 65 from the top rail, if desired.

It is obvious that the lugs h, for fastening the top rail to the lazy-back, may be welded to the rails of the latter, instead of to the former, 70 and inserted through and nutted to apertures in the top rail, E, if desired.

Having thus described our invention, we claim and desire to secure by Letters Patent of the United States—

1. The combination of the seat A, having seat-irons C and bracket-irons D, constructed as described, removable lazy-back L, provided with the rail F, having screw-threaded lugs f, and nuts G, and top rail, E, having extensions I, and provided with the screw-threaded lugs h, having nuts H, the whole constructed and combined substantially in the manner and for the purpose specified.

2. The combination of the top rail, E, having screw-threaded lugs h, lazy-back L, having rails F, perforated to receive the threaded lugs h, and nuts H, substantially as and for the purpose shown and specified.

In testimony that we claim the foregoing as 90 our own we have hereunto affixed our signatures in presence of two witnesses.

SAMUEL R. PARKER.
PAUL P. DEVENY.
